UNITED STATES PATENT OFFICE

2,663,953

EARTH MOVING MACHINE

Fredrick D. Cahill, Randolph, Ariz.

Application December 4, 1950, Serial No. 198,972

2 Claims. (Cl. 37—9)

1

This invention relates to new and useful improvements in earth moving machines, and more particularly pertains to improvements in the mounting of and the means for moving the component parts of machines of the type including an earth carrying bowl, and a rotatably mounted reel running between the bowl and a combined scraper blade and hood partially embracing the bowl.

The primary object of this invention is to support the bowl and its associated mechanism in an improved manner so that the vertical position of the same relative to the ground surface may be more effectively controlled during use of the machine for grading, scraping and loading, or hauling to the point of discharge.

Another important object of this invention is to increase the traction of a machine of this type so that the same may be more effectively employed on soft or broken surfaces making the use of present day equipment of this character difficult in the extreme, if not impossible.

Yet another important object of this invention is to positively drive the reel in a direction independent of the elevation of the same relative to the ground surface, and also independently of the direction of the advance of the machine.

A meritorious feature of the present invention resides in the provision of an auxiliary frame that is adjustable in height relative to the wheel supported frame, and which auxiliary frame is pivoted on a drive shaft rotatably mounted on the main frame, such drive shaft being drivingly connected to the reel.

Another important feature of the present invention resides in the drum, the head and scraping blade, and the reel all being carried by the auxiliary frame, together with means for adjusting the vertical height of the auxiliary frame relative to the main frame, whereby the force with which the scraper blade is urged downwardly may be increased until substantially the same as the entire weight of the machine with the reel then providing nearly all the traction of the machine by virtue of the same being disposed between the pairs of ground wheels and near the center of gravity of the machine.

Still another and the last important feature of the invention to be specifically set forth herein resides in the means provided for and carried by the auxiliary frame for rotating the bowl from a loading or carrying position to the dumping position, and the means by which the reel and the bowl are mounted on the side members of the auxiliary frame for rotation.

2

These, together with various ancillary objects and features of the invention which will become apparent as the following description proceeds, are attained by the present invention, a preferred embodiment of which has been illustrated by way of example only in the accompanying drawings, wherein:

Figure 1 is a side elevational view of the present invention showing the same in the process of being loaded, and showing certain portions of the machine that are concealed in dotted outlines;

Figure 2 is a top plan view of the present invention, concealed portions of the same being shown in dotted outlines;

Figure 3 is a vertical sectional view taken upon the plane of the section line 3—3 of Figure 2, with concealed portions of the same being shown in dotted outlines;

Figure 4 is a vertical transverse sectional view of the present invention, this view being taken upon the plane of the section line 4—4 of Figure 1 and showing concealed portions of the same in dotted outlines;

Figure 5 is a detail sectional view of a portion 25 of the means for rotating the drum, this view being taken upon the plane of the section line 5—5 of Figure 3;

Figure 6 is a diagrammatic side elevational view of the means provided for rotating the transverse shaft;

Figure 7 is a detail view in top plan of the power take-off and reversing mechanism for driving the transverse shaft, with portions of the housing for the transmission and the power take-off being removed to show the internal construction of the same;

Figure 8 is a detail view of a portion of the drive for the reel construction;

Figure 9 is a diagrammatic view of the hydraulic system utilized in the present invention for elevating the auxiliary frame and for rotating the drum; and

Figure 10 is a detail sectional view of the internal construction of one of the valves utilized in the hydraulic system.

Reference is now made more specifically to the accompanying drawings, wherein like numerals designate similar parts throughout the various views, and in which the machine constituting the subject matter of the present invention is designated generally at 10.

The machine 10 includes a main frame 12 comprising spaced frame members, which intermediate their ends have portions 16 offset outwardly 55 with respect to each other. The rear ends of

the frame members 14 are connected by a cross brace 18 and are suitably supported upon a spring mounted axle 20 having dirigible ground wheels 22 thereon. The wheels 22 are provided with a conventional steering linkage which includes steering arms 21 connected by a tie rod 23 whereby the wheels turn in unison. In the preferred form of the invention hydraulic means is provided for turning the wheels 22 which means includes a double acting hydraulic jack assembly 25, the cylinder of which is mounted on the axle 20 and the piston of which is pivoted to a steering arm 27 (see Figure 2.) The forward ends of the frame members 14 are supported on spring mounted traction wheels, and a prime mover, not shown, 15 is carried by the frame members 14 in advance of the traction wheels 24 by means not shown. An operator's cab 26 is supported on the forward ends of the frame members 14, in which cab is conveniently disposed a steering wheel 28 and the other controls necessary for controlling the operation of the machine, the steering wheel being provided with means, not shown, for controlling the hydraulic assembly 25.

As best shown in Figures 1-3, an auxiliary 25 frame is provided which includes spaced side members 30 disposed in parallel relation and above the parallel portions of the offset portions 16 of the frame members 14. While the rear extremities of the side members 30 are 30 connected by a crossbar 32, the forward ends of these members are rotatably mounted upon a transverse shaft 34, such transverse shaft 34 being journaled for rotation in suitable bearings 36 carried by the portions 16 of the frame members 14. It will thus be seen that the auxiliary frame may be swung in a vertical arc about the shaft 34 as a pivot relative to the main frame 12. As will be presently seen, means is provided for adjusting the angular relation of the auxiliary frame to the main frame, and for maintaining the frames in adjusted angular relationship.

An earth elevating reel construction 38 (see Figures 1, 3, and 4) is provided which includes spaced, parallel disks 40, the peripheries of which are connected by circumferentially spaced earth elevating vanes 42. The disks 40 are disposed between the side members 30, and have oppositely extending hollow hubs or axles 44 suitably journaled through the side members 30 at a position substantially equidistant from the wheels 22 and 24. It will be noted that the hubs 44 project through the members 30 and have toothed sprockets 46 rigidly affixed thereto for a purpose to be presently set forth, it being noted that suitable spacing means 48 is provided to prevent contact of the disks 40 with the side members 30.

A shaft 50 rotatably extends through the aligned hubs 44 and carries toothed sprockets 52 rigidly affixed to its opposite extremities for a purpose to be presently set forth. An earth carrying drum or bowl 54 is provided that is disposed within the reel construction 38. The top of the drum 54 is provided with an opening 56, and the opposite end walls 58 of the drum are provided with centrally disposed hollow bosses 60 which receive the shaft 50 therethrough, and such bosses 60 being suitably secured to the shaft 50 for rotation therewith. As best shown in Figures 1-3, an arcuate hood 62 is provided which partially embraces the rearmost portion of the reel construction 38, such hood 62 having

5 segmental parallel end walls 64 which are disposed between the side members 30 and rigidly secured thereto by fastening means 66. The lower edge of the hood 62 terminates in an integral scraper blade 68 that is disposed below the drum 54 and spaced rearwardly of the shaft 50, and as best shown in Figure 3, the scraper blade 68 is offset from the travel path of the vanes 42 to a greater extent than the hood 62. It will also be noted that the cutting edge of the scraper blade 68 is disposed upon substantially the same plane as the lower-most travel of the vanes 42.

As thus far described, it will be appreciated that upon advance of the machine 10, the scraper blade 68 will cut off the top layer of ground, and that the vanes 42 will be rotated by ground contact and run between the hood 62 and the bowl 54 to deposit the earth cut by the scraper blade 68 in the bowl 54 through the opening 56. It will be understood that the thickness of the layer of ground cut by the scraper blade 68 will be determined by the relative angular position of the auxiliary frame and the main frame.

In order to control the relative angular position of the auxiliary frame and the main frame, a double acting hydraulic jack 70 is provided which includes a cylinder 72 and a piston rod 74 extensible therefrom, the cylinder 72 being pivoted at 76 to a bracket 78 fixed on the hood 62, and the piston rod 74 being suitably pivoted at 80 to a cross member 82 connecting the frame members 14. Since the hood 62 is fixedly secured to the side members 30 of the auxiliary frame, it will be evident that upon extension of the hydraulic jack 70 the auxiliary frame will be elevated, and that upon retraction of the hydraulic jack 70 the auxiliary frame will be depressed relative to the main frame. The means for actuating the hydraulic jack 70 will be described shortly.

In order to rotate the drum or bowl 54 between the loading or carrying position of the same shown in Figure 3 to an inverted position 45 for dumping the contents thereof through the opening 56, a transverse shaft 84 is journaled through the side members 30. Levers 86 are fixedly secured intermediate their ends to the opposite extremities of the shaft 84, and the opposite ends of each of the levers 86 terminate in arcuate portions 88 that have peripheral grooves 90 formed therein. Flexible drive chains 92 are entrained over the sprockets 52 and have their opposite extremities fixedly secured to the arcuate portions 88 as at 94, such drive chains being entrained over the arcuate portions and disposed in the grooves 90 as will be readily understood upon reference to the drawings. It is therefore evident that rotation of the shaft 84 will be accompanied by rotation of the axle 50 and therefore the drum 54.

As best shown in Figures 1 and 2, the levers 86 are connected by a bar 94 so as to constitute a crank for rotating the levers 86. A hydraulic jack including a cylinder 96 and a piston rod 98 is provided that is of the double acting type, the piston rod 98 being pivotally connected to the bar 94 at 100, and the cylinder 96 being pivotally connected to the member 32 as at 102. It will thus be seen that extension of this hydraulic jack will cause clockwise rotation of the drum 54 as seen in Figure 1, while retraction of this jack will cause the drum to rotate in the 70 anticlockwise direction.

Attention is now directed to the means provided for actuating the hydraulic jacks. Referring to Figure 9, the hydraulic system is seen to include a hydraulic pump 104, which by means not shown is driven by the prime mover of the machine 10, a reservoir 106 which communicates with the low pressure side, or the intake of the pump 104 through a fluid line 108, and a bypass line 110 connecting the pressure side of the pump 104 to the reservoir 106 having a pressure relief valve 112 therein. A pair of control valves 114 and 116 are arranged in parallel between the hydraulic pressure line 118 and the return line 120 to the reservoir 106. Each of the valves 114 and 116 is of the type having the internal construction shown in section in Figure 10, wherein it will be noted that such valves include a valve casing having an inlet port 124, an outlet port 126, and lateral ports 128 and 130. A valve core 132 is rotatable in the valve casing 122 which is provided with passages 134 and 136 therein, the arrangement being such that the valve core 132 is rotatable from a position wherein the passage 134 communicates between the ports 124 and 128 and the passage 136 communicates between the ports 130 and 126 to a position wherein the passage 134 communicates between the ports 124 and 130 while the passage 136 communicates between the ports 128 and 126. Obviously, when the valve core 132 is rotated 45 degrees, the valve core 132 closes off communication between all of the ports in the casing 122. Inasmuch as the ports 128 and 130 are connected by a hydraulic circuit, it will be noted that the position of the valve core 132 determines the direction of fluid movement in such hydraulic circuit, or whether fluid movement in such hydraulic circuit will be permitted. Hydraulic lines 138 and 140 connect the ports 128 and 130, respectively, of the valve 116 to the opposite ends of the hydraulic cylinder 72, while hydraulic lines 142 and 144 connect the ports 128 and 130, respectively, of the valves 114 to the opposite ends of the hydraulic cylinder 96, whereby the movements of the piston rods 74 and 98 may be controlled. Obviously, the hydraulic assembly 25 may be incorporated in the hydraulic circuit between the lines 118 and 120 to be operated by the pump 104.

Attention is now directed to Figures 6-8 for a showing of the means employed for driving the transverse shaft 34. The numeral 146 designates a conventional transmission from the output shaft 148 of which power is transmitted through the universal joint 150 to the traction wheels 24. A power take-off designated generally at 152 is provided which includes a housing 154. Journaled in the housing 154 is a shaft 156 on which is slidable a toothed gear 158. The gear 158 is moved longitudinally of the shaft 156 by means of a bar 160 having engagement at one end by means of a yoke carried at one end engaging a grooved collar fixed to one side of the gear 158 as shown generally at 162, the bar 160 being adjusted in position by means of a shift lever 164 pivoted thereto at one end and being pivoted intermediate its ends to a bracket 166 carried by the housing of the transmission 146. As will be readily seen upon reference to Figure 7, the gear 158 is slidable on the shaft 156 into meshing engagement with a power driven gear 168. An output shaft 170 is journaled in the housing 154 and has a gear 172 fixed thereon, the gear 158 being movable into a position in meshing engagement with both the gears 168 and 172 to drive the output shaft 170. An idler gear 174 is rotatably mounted in the housing 154 in continuous mesh-

ing engagement with a further gear 176 fixed to the shaft 170, and the gear 158 may be moved from a position engaging the gear 176 to a position engaging the idler gear 174, in which latter position the gear 158 is still in mesh relation with the gear 168 to drive the output shaft 170 in a reverse direction to that when the gear 158 is engaged with the gear 172, as will be readily understood. Of course, no rotation will be imparted to the shaft 170 when the gear 158 is disposed in a position intermediate the gears 172 and 174.

The output shaft 170, through beveled gears 178 drives a transverse shaft 180 journaled between the frame members 14. The transverse shafts 34 and 180 are provided with toothed sprockets, over which is entrained a flexible chain 182, whereby the rotation of the shaft 180 is imparted to the transverse shaft 34.

As clearly shown in Figures 1 and 2, toothed sprockets 184 are fixedly secured to the opposite ends of the transverse shaft 34, and flexible chains 186 are entrained over the sprockets 184 and the sprockets 46, it being recalled that the latter mentioned sprockets are secured to the reel construction 38, whereby a positive drive is afforded the reel construction 38. It will also be appreciated that by virtue of the type of power take-off provided, the direction of rotation of the reel construction 38 may be controlled independent of the direction of advance of the machine 10.

The operation of the present invention will be readily understood. The bowl 54 may be loaded as shown in Figure 1, when power is being applied to the reel construction 38 in a clockwise direction, or when the latter is merely permitted to turn by virtue of its engagement with the ground. After the bowl 54 has been filled, the hydraulic jack 70 is extended to elevate the auxiliary frame, and the machine 10 driven to the point of discharge, at which time the hydraulic cylinder 96 is actuated to invert the bowl 54 so as to dump the contents thereof. As previously mentioned, the depth of cut made by the scraper blade 68 during the loading operation may be accurately controlled by the vertical position of the auxiliary frame. It will be appreciated that in soft ground or wherever traction for the machine is difficult, the positive drive to the reel construction 38 will materially assist the traction wheels 24 in propelling the machine. Since the reel is disposed intermediate the wheels 22 and 24, the auxiliary frame may be lowered to such a position that a very large portion of the weight of the entire machine is resting upon the reel construction, so that the latter may afford a very effective propelling means for the machine. It will be noted that the center of gravity of the machine is preferably disposed slightly forwardly of the reel, so that substantially the entire weight of the machine is disposed on the reel construction and the forward traction wheels 24. Inasmuch as the reel may be driven in a reverse direction relative to the direction of advance of the machine, an additional function of the present machine is possible, that is, the same may be used for grading. In other words, with the machine advancing in a forwardly direction as shown in Figure 1, it will be evident that if the reel construction 38 is rotating in a counterclockwise direction, the vanes 42 of the reel construction 38 will be moving forwardly with respect to the ground surface so as to spread and even the top material on the ground.

From the foregoing, the construction and operation of the device will be readily understood

and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. In an earth moving machine, a wheel supported frame, an auxiliary frame pivoted to the wheel supported frame for vertical swinging movement, means for adjusting and maintaining said frames in adjusted angular relation, a rotary bowl mounted on the auxiliary frame for rotation about an axis transverse to the fore and aft axes of the wheel supported frame, said bowl having an opening at the top thereof, a scraper blade spaced below the bowl and spaced rearwardly of said transverse axis, an arcuate hood extending upwardly from the scraper blade in spaced symmetrical relation to the bowl, said blade and hood being carried by the auxiliary frame, an earth elevating reel rotatably mounted on the auxiliary frame to rotate about the transverse axis and running between the hood and the bowl, and fluid pressure actuated means connecting the auxiliary frame and the bowl for rotating the bowl to dump the contents thereof through said opening, comprising said bowl having an axle rigidly affixed thereto, a toothed sprocket fixed on said axle, an elongated lever pivoted intermediate its ends to the auxiliary frame, said lever having its opposite ends terminating in arcuate portions, a drive chain entrained over the sprocket and rigidly secured to the arcuate portions, and a hydraulic assembly pivotally connected to the lever and the auxiliary frame.

2. An earth moving machine comprising a frame, forward and rear pairs of ground wheels supporting said frame, a prime mover drivingly connected to one of said pairs of ground wheels, a shaft mounted for rotation on the wheel supported frame transversely thereof, an auxiliary

frame having one end pivotally mounted on the shaft for vertical swinging movement, a hydraulic cylinder connected to said wheel supported frame for adjusting and maintaining said frames in adjusted angular relation to control the height of the auxiliary frame, a rotary bowl secured to an axle carried by said auxiliary frame for rotation about an axis located intermediate said ground engaging wheels and parallel to said shaft, 10 said bowl having an opening at the top thereof, a ground-engaging scraper blade spaced below said bowl and rearwardly of the axis thereof, an arcuate hood extending upwardly from said scraper blade in spaced concentric relation to said bowl, said hood being rigidly secured to said auxiliary frame, said hydraulic cylinder for maintaining said frames in adjusted position being carried by said hood, an earth elevating reel mounted on said auxiliary frame for rotation 15 about the axle of said bowl between said bowl and said scraper, drive means connecting said prime mover to said shaft for selectively rotating same, flexible drive means connecting said shaft so said reel for rotating same, a toothed sprocket carried 20 by the axle of said bowl, an elongated lever pivoted intermediate its ends to said auxiliary frame, said lever having arcuate end portions, a drive chain entrained over said sprocket and rigidly secured to said arcuate portions, a second hydraulic 25 cylinder connected to said auxiliary frame and said lever for rotating said bowl, hydraulic pump means for said hydraulic cylinders driven by said prime mover.

FREDRICK D. CAHILL.
